UNITED STATES PATENT OFFICE.

JOHN E. BLACKMORE, OF DETROIT, MICHIGAN.

DESIGN FOR A SPRING-RETAINING WASHER.

52,425.

Specification for Design.

Patented Sept. 17, 1918.

Application filed April 1, 1918. Serial No. 226,095. Term of patent 14 years.

To all whom it may concern:

Be it known that I, JOHN E. BLACKMORE, a citizen of the United States, and resident of Detroit, in the county of Wayne and State of Michigan, have invented a new, original, and ornamental Design for Spring-Retaining Washers, of which the following is a specification, reference being had to the accompanying drawing, forming a part thereof.

Figure 1 is a perspective view of a spring retaining washer showing my new design.

Fig. 2 is a cross section taken on line $\alpha-\alpha$ of Fig. 1.

I claim:

The ornamental design for a spring retaining washer as shown.

JOHN E. BLACKMORE.
